UNITED STATES PATENT OFFICE.

JAMES A. PACKARD, OF MILWAUKEE, WISCONSIN.

BOILER FURNACE.

Application filed April 22, 1921. Serial No. 463,441.

To all whom it may concern:

Be it known that I, JAMES A. PACKARD, a citizen of the United States, and resident of Milwaukee, in the county of Milwaukee and State of Wisconsin, have invented new and useful Improvements in Boiler Furnaces, of which the following is a description, reference being had to the accompanying drawings, which are a part of this specification.

The invention relates to stokers, more particularly for boilers and of the inclined reciprocating grate type.

One of the objects of this invention is to provide a stoker having a grate composed of a plurality of reciprocating grate units, adjacent units moving in opposite directions with a feed slide carried by those units moving in the same direction so as to advance the fuel over the grate, said units being disposed on an inclined support to facilitate the movement of the fuel.

A further object of the invention is to provide a reciprocating grate unit made up of a plurality of removable grate sections.

A further object of the invention is to provide an agitating mechanism in the feed hopper to prevent clogging of the fuel therein.

A further object of the invention is to provide improved means for dumping and crushing the ash.

A further object of the invention is to provide means for furnishing blast air to the grates and to indicate the pressure of the air.

A further object of the invention is to provide air conduits between the sides of the grates and the outer walls of the furnace.

The invention further consists in the several features hereinafter set forth and more particularly defined by claims at the conclusion hereof.

In the drawings: Fig. 1 is a side elevation view of a stoker embodying the invention; Fig. 2 is a plan view thereof, parts being broken away; Fig. 3 is a front end view of the furnace; Fig. 4 is a section taken on the line 4—4 of Fig. 2; Fig. 5 is a section taken on the line 5—5 of Fig. 4; Fig. 6 is a detail view showing a modified form of feed slide.

The furnace frame includes front columns 8, rear columns 9, inclined side members 10 mounted on these columns and con-

nected at their lower ends to a bottom frame member 11. The columns 8 are connected together by a front plate 12 and doors 13 hinged to the end columns provide access to the space beneath the grates. The side frame members 10 have metal blocks 14 removably mounted thereon and these blocks have laterally extending upwardly inclined portions 15 extending to the brick side wall 16 and provided with openings 17 to permit air to pass from the pit into the space above the grates, the passage of air acting to cool the blocks. The bottom frame member 11 has metal blocks 18 removably mounted thereon.

The furnace shown is constructed with grates between the outer and middle columns 8. Each grate comprises a plurality of movable grate sections 19 and each grate section is made of a plurality of grate units 20. The units 20 forming a grate section are secured together in any suitable manner, as by lugs 21 insertable between spaced projections 22 upon a supporting grate bar 23, the lugs of adjacent units abutting each other and having a suitable fit between the lugs 21 on the bar 23. This feature permits of ready renewal of those parts of the grate section which need renewal without having to replace the whole grate section. The upper grate unit 24 of each section is preferably of stepped formation, having air holes 25 therein, and the other units of the section are of arched formation having air holes 26 therein, the size or number of these holes 26 increasing from that of the preceding grate unit so that the supply of air to the fuel is increased as the fuel travels from the upper end of the grate down to the bottom thereof.

The grate bar 23 for each section has T-shaped projections 27, the flange portions 28 of which ride on the flanges 29 of rollers 30 and the web portions 31 of which are disposed between said flanges. The rollers 30 are loosely mounted on upper and lower shafts 32 secured to the side frames 10. This construction permits each grate section to move up and down in an inclined position, the connection between the bars and the rollers keeping the grate sections in alignment.

Adjacent grate sections are preferably moved in opposite directions and to accomplish this, alternate grate sections are each connected by a link 33 to one arm of a le-

ver 34 on a rock shaft 35, and the other sections are each connected by a link 36 to the other arm of said lever. A crank arm 37 is secured to the shaft 35 and connected to a piston rod 38 carried by a piston in a steam cylinder 39 which constitutes a motor. The piston and steam cylinder and details are not shown in full, as they are such as are commonly employed on steam pumps.

10 A stepped movable feed slide 40 forms the bottom of a feed hopper 41 for each grate and is preferably secured to alternate grate sections by bolts 42 so as to move therewith and opposite to the movement of the other grate sections. Instead of making one slide serve for each grate, stepped feed slides 40' may be connected to each grate section and move therewith, as shown in Fig. 6. The wall of the hopper adjacent the fire 15 brick arch 43 is formed by plates 44 and 45 spaced apart to form an air space 45' between them to keep the outer plate 45 cool. These plates are secured together by providing spaced wedge lugs 46 on the plate 44 20 passing through openings 47 in the plate 45 with wedge blocks 46' between the lugs 46, the plate 45 having spacing lugs 48.

In order that the coal may be prevented from packing in the hopper and thereby interfering with its proper feed, an agitating mechanism is provided comprising an endless conveyor or impeller 49 formed of spaced rods 50 and chains 51, the latter being mounted on rollers 52 and drive sprockets 53. The shaft 53' carrying the sprockets 53 projects outside of the hopper and carries a ratchet wheel 54 engaged by a spring 30 pressed pawl 55 on a lever 56 rocked by the crank arm 37 through a link 57. The rocking of this lever 56 causes the pawl and ratchet mechanism associated therewith to give the shaft 53' an intermittent rotary movement so that the conveyor is given a step-by-step movement in a direction toward the interior of the furnace. This movement of the conveyor keeps the coal from packing and cooperates with the slide 40 in feeding the fuel to the grates.

45 A discharge opening 58 is provided between each slide 40 and the plate 45. With the machine in operation the coal is moved on each grate by the conveyor 49 and the slide 40 through the opening 58, the slide 40 moving downwardly with alternate grate sections as the other sections move upwardly, and this action serves to advance the fuel along the grates, the fresher fuel pushing the partially consumed fuel ahead of it. By the time a charge of fuel has reached 50 the lower end of the grate it has been consumed and is dumped into the ash pit by means of dumping grates 59 and 60. The grate 59 is pivotally mounted at its rear end at 61 and tips upwardly to prevent fuel on 55 the main grates from passing to the pit

when the clinker or ash is discharged between this grate and the grate 60. It is tipped by means of a crank arm 62, link 63 and lever 64 which engages a pin 65 with the grate 59 in its normal position and is moved to dotted line position by a pipe or other suitable device. The grate 60 is pivotally mounted at its rear end at 63' and connected to a toggle link 64', said link being connected to a toggle link 65' pivoted on the frame. A link 66 connects the links 64' and 65' with a lever 67 which in its normal position engages a stop 67'. When the lever 67 is thrown rearward the pivots of the toggle move out of line and the grate 60 moves to the dotted line position shown in Fig. 4.

The columns 8 are made hollow and have inlets 68 in their lower ends communicating with blast air conduits 69 and outlets 70 at 85 their upper ends communicating with an air box 71 extending from the front plate 12 to a fixed frame member 72 upon which lower end of the grate sections slide, the plate 73 forming the bottom of the box being removable from the front of the furnace so as to prevent fine ashes from the grates collecting therein and for changing from "forced" to "natural" draft.

90 It is quite important to maintain the air pressure sufficient for proper combustion and in order that this pressure may be indicated an air pressure gage 74 is mounted on the front plate and is provided with a tube 75, the inner end of which extends into the region below the grates where combustion is taking place.

95 As the adjacent grate sections of each grate move in opposite directions, the fuel on the grate sections is kept in a state of motion by this action, as well as by the incoming fuel pushing the older fuel ahead of it down the grate sections.

100 The design of the air ports or holes 26 in the grate units may be of different shapes, as indicated in Fig. 2, where only the units of one grate section are shown in detail. The edges of the grate units are preferably provided with notches or recesses 76 forming air holes.

110 I desire it to be understood that this invention is not to be limited to any specific form or arrangement of parts except in so far as such limitations are specified in the claims.

115 What I claim as my invention is:

1. In a furnace, the combination of a hopper having a reciprocating bottom feed slide and a discharge opening adjacent thereto, a plurality of inclined reciprocable grate sections having their upper ends adjacent said discharge opening and connected to said feed slide to move therewith, an endless impeller disposed in said hopper with its lower run adjacent said feed slide, and

means for imparting a step by step movement to the lower run of said impeller toward said discharge opening and in synchronism with the movement of said feed slide toward said opening.

2. In a furnace, the combination of a plurality of grate sections disposed and movable on an incline and having air openings therein, a stationary air box forming a duct for blast air disposed beneath said sections and provided with an inclined bottom closure plate extending substantially the length of said sections and removable from the front of the furnace.

3. In a furnace, the combination, with inclined supporting means, of a grate section comprising a grate supporting bar movable on an incline on said supporting means, and a plurality of grate units detachably secured to said bar, the upper unit being of

stepped formation and the other units being of longitudinally arched formation.

4. In a furnace, the combination of a hopper having a reciprocating bottom feed slide and a discharge opening adjacent thereto, a plurality of movable grate sections disposed and movable on an incline, means for moving adjacent grate sections in opposite directions, said feed slide being connected to alternate grate sections to move therewith, an endless impeller disposed in said hopper with its lower run adjacent said feed slide, and means for imparting a step-by-step movement to the lower run of said impeller in the direction of said delivery opening.

In testimony whereof, I affix my signature.

JAMES A. PACKARD.
